CLAIM

The ornamental design for a triangular lighting unit, as shown and described.

DESCRIPTION

FIG. 1 is a perspective view of the right side and rear of the triangular lighting unit in accordance with the new design, showing a pole in dashed lines that supports the triangular lighting unit;

FIG. 2 is a perspective view of the left side and rear of the triangular lighting unit in accordance with the new design, showing a pole in dashed lines that supports the triangular lighting unit illustrated in FIG. 1;

FIG. 3 is a front elevational view of the triangular lighting unit illustrated in FIGS. 1-2;

FIG. 4 is a left side elevational view of the triangular lighting unit illustrated in FIGS. 1-3;

FIG. 5 is a right side elevational view of the triangular lighting unit illustrated in FIGS. 1-4;

FIG. 6 is a top plan view of the triangular lighting unit illustrated in FIGS. 1-5; and,

FIG. 7 is a bottom plan view of the triangular lighting unit illustrated in FIGS. 1-6.

The dashed lines shown on the drawings are for illustrative purposes only and form no part of the claimed design.
